UNITED STATES PATENT OFFICE.

WILLIAM JOHN GLOVER, OF ST. HELENS, ENGLAND.

SYSTEM OF ERECTING AND ADJUSTING BRIDGE SUSPENSION-CABLES.

SPECIFICATION forming part of Letters Patent No. 709,316, dated September 16, 1902.

Application filed April 29, 1902. Serial No. 105,135. (No model.)

To all whom it may concern:

Be it known that I, WILLIAM JOHN GLOVER, engineer, a subject of the King of Great Britain, residing in St. Helens, in the county of 5 Lancaster, England, (whose full postal address is Liverpool road, St. Helens, aforesaid,) have invented certain new and useful Improvements in Systems of Erecting and Adjusting Bridge Suspension-Cables, (for which 10 application has been made in England under No. 20,739, dated October 16, 1901,) of which the following is a specification.

This invention has for its object a system 15 of erecting and adjusting bridge suspension-cables in such manner as, first, it will not interfere with the traffic beneath; secondly, there will be no occasion to send people along the cables to remove the suspension-clips, and, thirdly, so that the cables already laid 20 shall not be frayed or endangered by the laying of another alongside of them.

In the accompanying drawings, Figure 1 is 25 a front view illustrating my system for erecting and adjusting bridge suspender-cables; Fig. 2, a plan; Fig. 3, side and end views of the two forms of clamp.

I first carry a temporary cable A or traveler across from one terminal suspension-tower B to the other C by boats or other means and 30 pass it over pulleys D, placed about four feet above each saddle E. This temporary cable is then brought down under a guide-pulley F at one end or pier c to a back pulley G, thence several times around a pulley H, 35 worked by a winch I, thence over a second back pulley J, and then under a guide-pulley K to a second pulley L, arranged about four feet above the saddle E, in line with the first D, thence across the space to be bridged to a 40 similar pulley M, above the other saddle, thence down the tower for some distance to a tension-sheave N and back again to a pulley O on the same shaft as M, thence around guide-pulleys P and back pulleys Q to the 45 other end or pier b. The two ends of the temporary cable A are now spliced and it becomes an endless rope, the slack being taken up when the splicing has been effected by the winch S. There may be one or two tension- 50 sheaves, if required. These tension-sheaves are drawn down by a block-tackle R, connected with the winch S. The steam-winches

is now started slowly. At the same time the slack is taken up by the tension-blocks R and subsidiary winch S, tension being applied until the temporary cable or traveler is sufficiently taut and any superfluous rope is caught up and all strained up. When it is found to run smoothly, a drum containing the first suspender-cable is placed in position and the cable end secured to the temporary cable or traveler A by means of clamps U, Fig. 3, at a point just above the pulley P. These clamps U are formed of cheeks which grip both the suspender-cable and the traveler 65 A, bolts t being employed to fasten the two cheeks together. In the case of a thousand-feet-span bridge, which I expect shortly to lay, the cables, (the traveler A and permanent one,) will be secured together at intervals of 70 about thirty yards by preference with these clamps firmly attached to both cables. The steam-winches now slowly travels the traveler A, pulling the suspender-cable upward, and as the leading clamp with its suspender-cable approaches the pulley D over saddle E 75 the cable is attached by similar clamps to the forward side of the saddle and clamp on rear side removed. As the traveler hauls up the cable additional running-clamps V are fixed 80 after passing the saddle every twenty yards or so. These clamps V are also formed with a pair of cheeks; but they are so arranged that they are clamped tight to the traveler A only, the permanent cable T passing freely 85 through a hole W, bell-mouthed on each side and of a larger diameter than the cable. As the traveler A arrives at the opposite saddle the first or fixed clamp U is removed and again refixed after passing the saddle, and 90 the cable is carried down until the prepared end with attachment comes off the drum, this end being secured at X in a bridge-piece by straining-screws. The fixed clamps are kept on and the traveler A is slackened by means 95 of tension-sheave R and winch S until the correct deflection of the permanent cable T is obtained. It is now securely held in position on the saddles by suitable caps and screws. The first fixed clamp and any others 100 which are still fastened are now removed, and the anchor-block and adjusting-screw sleeve are put on and passed into place with the assistance of the power from the steam-

winch. When the permanent cable T is finally fixed to the correct deflection and fixed clamps removed, traveler A draws the remaining free clamps V to the saddle, where they are removed, leaving the suspender-cable T free. The traveler A can now be used for placing another cable in position in like manner. It will also be seen that as the traveler is an endless cable passing twice over the space to be bridged if two of the permanent cables be started from opposite ends they can both be drawn over at same time by the two sides of the temporary cable. The clamps in order to avoid fraying the cables already laid have all their surfaces rounded, and the heads and nuts of the bolts *t*, clamping the two halves together, are in depressions and do not project beyond the surface of the clamps. The clamps are by preference of brass or copper, so as to lessen the chance of injuring the cable. It is obvious that it is not absolutely necessary to have an endless cable. It could be arranged for the winch to wind up a single length of cable.

Among the advantages of the system are that instead of the permanent cable T hanging slack and being drawn up at heavy strain to its correct deflection it is placed in position first above its correct deflection, and therefore is easily lowered down into position, while at the same time any chance of interfering with the traffic below is avoided. As the clamps V, too, are loose on the permanent cable and can be drawn by the traveler to one pier or the other to be removed, there is no occasion for the very dangerous plan at present adopted of sending men across the place to be bridged in cradles to detach the clamps or clamping devices, while the arrangement of my clamps is such that there is no chance of injuring the cable.

I declare that what I claim is—

- An apparatus for erecting and adjusting bridge suspension-cables, comprising a length of temporary cable passing over the space to be bridged from one pier to the other, pulleys on the piers and on the suspension-towers over which said temporary cable runs, clamping devices for attaching one end of the suspender-cable to the temporary one, means

for driving said cable so that it will act as a traveler and haul the suspender-cable from one pier to the other, and devices for straining up and slackening said temporary cable, whereby the suspender-cable is first placed in position above its correct deflection and can afterward be lowered into position, while at same time any chance of interfering with traffic below is avoided. 55

2. For erecting and adjusting bridge suspender-cables, a temporary endless cable or traveler passing twice over the space to be bridged, pulleys on the piers and suspension-towers over which the temporary cable can run smoothly, a winch for driving said cable 60 so that it will act as a traveler to draw the permanent cable over from one end, or from opposite ends at the same time, and tension-sheaves and a subsidiary winch for straining up any superfluous cable and making it taut, 70 and for slackening said temporary cable so as to secure any desired deflection.

3. In apparatus for erecting and adjusting bridge suspender-cables, the combination with the traveler of a clamp for securing the 75 suspender-cable thereto, consisting of a pair of cheeks adapted to grip both the cable and the traveler and bolts for binding the two cheeks together, the heads and nuts being in depressions in the cheeks so as not to project 80 beyond the surface of the clamps.

4. In apparatus for erecting and adjusting bridge suspender-cables, the combination with the traveler of clamps V for hanging the suspender-cable (at intervals of twenty yards 85 or so) from the traveler, each consisting of a pair of cheeks adapted to grip the traveler only but loose on the permanent cable so that they can be drawn by the traveler to one pier or the other to be removed, whereby there is 90 no occasion for sending a man across the place to be bridged in cradles to detach the said clamps.

In witness whereof I have hereunto signed my name, this 18th day of April, 1902, in the 95 presence of two subscribing witnesses.

WILLIAM JOHN GLOVER.
